US0D1092505S

(12) **United States Design Patent** (10) Patent No.: **US D1,092,505 S**
 Davis et al. (45) Date of Patent: ** Sep. 9, 2025

(54) **DISPLAY SCREEN OR PORTION THEREOF WITH GRAPHICAL USER INTERFACE**

- (71) Applicant: **Tyco Fire & Security GmbH**, Neuhausen am Rheinfall (CH)
- (72) Inventors: **Robbie G. Davis**, Kew Gardens, NY (US); **Kerry M. Bell**, Mukwonago, WI (US); **Rajesh Nayak**, Karnataka (IN); **Kierstyn R. Robbins**, Milwaukee, WI (US); **Ann M. Cook**, Neshkoro, WI (US)
- (73) Assignee: **TYCO FIRE & SECURITY GMBH**, Neuhausen am Rheinfall (CH)
- (**) Term: **15 Years**
- (21) Appl. No.: **29/890,288**
- (22) Filed: **Apr. 21, 2023**
